(57) **CLAIM**

The ornamental design for a cloverleaf flowerpot, as shown and described.

DESCRIPTION

FIG. 1 is a top plan view of a cloverleaf flowerpot embodying my new design, the design including a flowerpot portion and a drip pan portion, the illustrated portion being the flowerpot portion;

FIG. 2 is a bottom plan view of the flowerpot portion thereof;

FIG. 3 is a front elevational view of the flowerpot portion thereof, the rear, left, and right side elevational views thereof being the same;

FIG. 4 is a front, top, and left side perspective view of the flowerpot portion thereof;

FIG. 5 is a rear bottom, and right side perspective view of the flowerpot portion thereof;

FIG. 6 is a top plan view of the drip pan portion of the cloverleaf flowerpot;

FIG. 7 is a bottom plan view of the drip pan portion thereof; and

FIG. 8 is a front elevational view of the drip pan portion thereof;

FIG. 9 is a front, top, and left side perspective view of the drip pan portion thereof;

FIG. 10 is a rear, bottom, and right side perspective view of the drip pan portion thereof; and,

FIG. 11 is a front, top, and left side perspective view of the flowerpot portion nested in the drip pan portion.

The evenly spaced broken lines showing environment in the drawings are for information purposes only and form no part of the claimed design. The long and short broken lines which define the bounds of the claimed design form no part thereof.
